UNITED STATES PATENT OFFICE.

THOMAS W. MEREDITH, OF NEW YORK, N. Y.

SHOE.

1,158,526.

Specification of Letters Patent.

Patented Nov. 2, 1915.

Application filed July 23, 1914. Serial No. 852,545.

To all whom it may concern:

Be it known that I, THOMAS W. MEREDITH, a subject of the King of Great Britain, and a resident of the borough of Manhattan of the city, county, and State of New York, have invented certain new and useful Improvements in Shoes, of which the following is a specification.

The invention relates to shoes having an elastic member in the upper thereof and particularly to shoes of the type that are constructed so that the shoe can be placed on the foot without buttoning or lacing the shoe.

According to one phase of the invention, it particularly relates to high shoes that have the resemblance of a button shoe, having the exposed portion of the upper made of fabric in which there is woven elastic bands.

As showing certain specific embodiments of the invention, reference is made to the drawings forming a part of this specification and in which drawings,—

Figure 1 is a side elevation of one form of shoe. Fig. 2 is a plan view of the shoe shown in Fig. 1. Fig. 3 is a section taken through the upper of the shoe shown in Fig. 1 and is a view taken on the line 3—3 of said Fig. 1, looking in the direction of the arrows. Fig. 4 is a side elevation of another form of high shoe. Fig. 5 is a plan view of the shoe shown in Fig. 4. Fig. 6 is a sectional view taken through the upper of the shoe shown in Fig. 4 and is a view taken on the line 6—6 of said Fig. 4, looking in the direction of the arrows.

In Fig. 1, 1 represents the sole of the shoe, 2 represents the shank and 3 represents the heel.

In the form of shoe shown in said Fig. 1, the inelastic flexible vamp or forward exposed member 4 is secured to the sole and to the shank of the shoe, while the counter covering or inelastic exposed rear member 5 is connected to the heel and to the shank of the shoe. In the form shown in this figure, however, the members 4 and 5 are not directly secured together but are separated by the portion 6.

For the sake of convenience the exposed portion of the shoe which is at the right side 7 of the right shoe, is arbitrarily referred to as the outside of the shoe, while the exposed portion at the left side 8 of the same shoe is arbitrarily referred to as the

inside of the shoe. Correspondingly the left side of the left shoe is referred to as the outside of the shoe, while the right side of the left shoe is referred to as the inside of the shoe.

The part 6 which extends downwardly between the vamp and the counter covering portion 5 is located on both the inside and the outside of the shoe, whereby there can be a uniform break along the shank which will be imparted to the material constituting the portion 6 of the upper part of the shoe, thus allowing the vamp 4 and the counter member 5 to remain smooth when the shoe is on the foot.

The upper of the shoe shown in Figs. 1 to 3 comprises the elastic fabric outer part 9 and the elastic fabric inner part 10 that are secured together at the front and the rear by the inelastic connecting or binding straps 11, 12, 13 and 14 which may be either of fabric or leather or of a combination of both. The outer part 9 may be considered to comprise the main member 15 and the fly or fly portion 16. In the form of shoe shown in Figs. 1 to 3, the fly is made a separate member from the main member 15 and it can be secured in the desired position as by the stitching 17 which passes through the ornamental buttons 18 and the forward portion of the main member 15. Due to this construction, the upper can be changed to fit the particular wearer and when once the parts are secured together as in the manner indicated, the two form a comparatively continuous member, thus forming the outer part 9.

The elastic fabric of the fly or fly portion 16 is reinforced by an inelastic but flexible backing as leather 19 which prevents the fly from stretching, in other words, a backing which kills or neutralizes the elastic effect of the fly portion thus reinforced, thus giving the fly the same uniform look when on the foot as when off, but at the same time allowing all other parts of the elastic upper to conform to the ankle of the wearer. The top line or edge 20 of the upper is a selvage edge and the elastic bands are woven in the fabric parallel to this selvage edge. With the exception of the binding straps 11 and 14 and the binding strap 16^a, all of the exposed portion of the upper is an elastic fabric which resembles an ordinary woven fabric. As the whole shoe upper, with the exception of the backed fly, is free to stretch

to conform to the ankle of the wearer, no lining is provided within the shoe upper.

In the form of shoe illustrated in Figs. 4 to 6, the vamp and the counter are provided in a continuous piece while the upper is secured thereto. The upper in the form shown in Figs. 4 to 6 comprises an elastic inner part 21 and an elastic outer part 22. The outer part may be considered to comprise 10 the main portion 23 and the fly portion 24. In this form of shoe the fly and main portion are both of the same piece of material, that is they constitute an integral member. The fly portion is reinforced or backed with 15 a piece of leather or other inelastic flexible material for its full width and length, as in the case of the shoe shown in Fig. 1, whereby there will be no stretching of the button fly. In other words the leather or other inelastic flexible backing neutralizes the elastic effect of the button fly portion.

In the form of shoe shown in Figs. 1 to 3 and in the form shown in Figs. 4 to 6, the button fly is prevented from stretching and 25 therefore it is necessary to provide what would ordinarily appear to be an excess of fabric material in the outside of the shoe and an insufficiency of material in the inside of the shoe. Thus, when the shoe is off the 30 foot, and is in the position shown in Figs. 2 or 5, the forward seam of the shoe appears to be drawn inwardly, for instance toward the left of the right shoe, while the rear seam of the shoe appears to be centrally located at the rear of the shoe. This distorted appearance is all corrected when the shoe is placed upon the foot. It will be noted that the elastic fabric constituting the upper parts 35 of the shoe may be made of any fabric material such as is often now referred to as rubberized velvet, that stretches like goring, whereby the shoe can be pulled on and taken off similar to Congress shoes of former days. In high shoes the buttons are preferably 40 stitched to the fly, which in turn may be stitched directly to the quarter, or main member; see 15 of Fig. 1.

It is obvious that various changes and modifications may be made without departing 50 from the spirit and scope of my invention.

What I claim is:

1. A shoe having an upper formed of fabric with elastic woven therein, which upper comprises inner and outer members that 55 are secured together at the front of the shoe and also at the rear of the shoe, the outer member comprising a main portion and a fly portion which together constitute an integral member, said fly portion being backed on the side not exposed with a flexible inelas-

tic portion for preventing said fly portion from stretching.

2. A shoe having a vamp and an upper, the upper being formed of fabric in which 65 there is woven elastic so that the upper can conform to the ankle of the wearer, the upper comprising an exposed inner member and an exposed outer member, the outer exposed member comprising a main portion 70 and a false fly portion which is integral with said main portion, said main portion being connected at the rear of the shoe to the inner member and said fly portion being connected at the front of the shoe to the inner 75 member, said fly portion being provided with a flexible inelastic backing to neutralize the elastic effect of the portion thus backed.

3. A high shoe having the exposed portion of the inner and outer parts formed of fabric 80 material with elastic woven therein whereby the shoe can be readily removed from the foot and whereby, when the shoe is in place on the foot, the inner and outer parts will fit the ankle, there being a rear seam in said 85 shoe at the junction of said inner and outer parts, which seam appears to be centrally located both when the shoe is on and off the foot of the wearer, and there being a front seam in said shoe at the junction of 90 said parts which last mentioned seam appears to be drawn toward the inner side of the shoe when the latter is off the foot, but which distorted appearance is corrected when the shoe is in place on the foot, the 95 outer part of said upper having secured to a portion thereof an inelastic flexible backing which neutralizes the elastic effect of the portion to which the backing is secured.

4. A shoe having a vamp and an upper, 100 the upper being formed of fabric in which there is woven elastic so that the upper can conform to the ankle of the wearer, the upper comprising an exposed inner member and an exposed outer member, which members are connected together at the rear and forward parts of the shoe, said outer exposed member comprising a main portion in which the elasticity has not been neutralized and a fly portion in which the elasticity has been 110 neutralized, which main portion extends from the rear of the shoe to the fly portion and which fly portion extends from the front of the shoe to the said main portion, both of which portions are integral with 115 each other.

This specification signed and witnessed this 22nd day of July, A. D. 1914.

THOMAS W. MEREDITH.
